[57] CLAIM

The ornamental design for a foregrip for a fishing rod, as shown and described.

DESCRIPTION

FIG. 1 is a side elevational view of a foregrip for a fishing rod, showing our new design;

FIG. 2 is a perspective view of a foregrip for a fishing rod showing our new design;

FIG. 3 is a rear elevational view thereof;

FIG. 4 is a side elevational view thereof;

FIG. 5 is a front elevational view thereof;

FIG. 6 is a top plan view thereof;

FIG. 7 is a bottom plan view thereof.

The broken line showing of the rod, reel, and hand is for illustrative purposes only and forms no part of the claimed design.
